FIG. 3.

FIG. 4.

A technical drawing of a circular component, likely a bearing or bearing housing, mounted in a rectangular housing. The central part has a spiral pattern and is labeled '86'. The outer ring is labeled '86' and '94'. The housing has four rectangular cutouts, each labeled '86' and '94'. The overall assembly is labeled '19' at the bottom and '82' on the right side.

A cross-sectional diagram of a disc with multiple concentric layers. The outermost layer is labeled 'B' at the top right. The next layer inward is labeled '17' at the top right. The next layer is labeled '15' at the top right. The next layer is labeled '10' at the top right. The innermost layer is labeled 'A' at the top right. The label '110' is placed in the upper left quadrant, and '98' is placed in the lower right quadrant. The layers are depicted with different hatching patterns: the outermost layer has a fine cross-hatch, the next has a coarse cross-hatch, and the inner layers have a vertical hatching.

UNITED STATES PATENT OFFICE

LUTHER A. GAW, OF CHARLOTTESVILLE, VIRGINIA, ASSIGNOR TO DILLON-GAW MOTOR COMPANY, OF FAYETTEVILLE, WEST VIRGINIA, A CORPORATION OF WEST VIRGINIA

CYLINDER-HEAD CONSTRUCTION FOR INTERNAL-COMBUSTION ENGINES

Application filed January 24, 1927. Serial No. 163,193.

This invention relates to improvements in cylinder casing block and head construction for internal combustion engines, particularly of the sleeve valve type.

The primary object of this invention is the provision of an improved cylinder head construction for internal combustion engines, embodying individual cylinder heads for the cylinders of an internal combustion engine, and an improved hood for guiding the circulation of water about all of the cylinder heads of the engine.

Other objects and advantages of this invention will be apparent during the course of the following detailed description.

In the accompanying drawings, forming a part of this specification, and wherein similar reference characters designate corresponding parts throughout the several views,

Figure 1 is a longitudinal sectional view showing details of the internal combustion engine, and more particularly the head construction, during an operation of parts just before the exhaust is ready to take place.

Figure 2 is a longitudinal sectional view taken through the cylinder construction of the internal combustion engine, showing more particularly the arrangement of parts during the start of the power stroke.

Figure 3 is an enlarged sectional view of the head construction of the internal combustion engine cylinder, showing the exhaust position.

Figure 4 is a sectional view of details taken at right angles in the view illustrated in Figure 3, substantially on the line 4-4 of Figure 3.

Figure 5 is a sectional view taken substantially on the line 5-5 of Figure 4.

Figure 6 is a sectional view taken substantially on the line 6-6 of Figure 1.

Figure 7 is a fragmentary view, partly in section, showing the cylinder's intake port with the adjacent intake port of the sleeve valve of the engine just starting to open.

Figure 8 is a fragmentary view, partly in section, showing means upon which the cams directly engage for causing an operative movement of the sleeve valve.

In the drawings, wherein for the purpose of illustration is shown only a preferred em-

bodiment of the improved sleeve valve internal combustion engine, the letter A may generally designate the engine, which may include the cylinder block or casing construction B which includes a crank case C wherein a crank shaft D is rotatably mounted. A piston E operates in each of the cylinders of the engine, connected by a rod F to the crank shaft D in the usual manner. A sleeve valve G operates in each cylinder between the piston and the cylinder walls, and the sleeve G is controlled by cam means H operating on means L which is connected with the sleeve valve. A detachable cylinder head construction M is provided for each cylinder of the engine A, and preferably only a single novel water hood or manifold P is provided for cooperation upon the cylinder block B and with the cylinder heads M, to regulate the flow of the cooling medium.

The cylinder block B is preferably provided with any approved number of cylinder chambers 15, each of which open directly on the top surface of the cylinder block B, and in the upper openings of the cylinder chambers 15 detachable individual cylinder heads M are adapted to be positioned in a novel relation to be subsequently described. The cylinder block B is of course provided with a water jacket, providing water compartments 17 surrounding each cylinder, and these water compartments have outlets 19 directly on the top surface of the cylinder block, so that the water may circulate about the cylinders thru the openings 19 into the water hood or manifold P and about the individual detachable cylinder heads M for cooling the latter, in the relation of parts to be more fully detailed hereinafter.

For each cylinder chamber 15 the block B is provided with an upper transverse intake port 22 and an opposite but preferably lower exhaust port 23; these ports being preferably tapered in a converging relation towards and into their respective cylinder chambers 15 wherein the sleeve valves G are slidable. Suitable oil ducts 24 may be provided in the block B for oiling the piston and sleeve action, in any approved relation.

The cylinder block B is of course mounted

on the crank case C in any approved and conventional relation, and the crank shaft D is conventionally connected to the pistons E.

The sleeve valves G are provided in each of the cylinder chambers 15 in snug sliding relation therein and each of these sleeve valves G includes an upper transverse intake port 26 and an opposite but preferably lower exhaust port 27 adapted to cooperate respectively with the ports 22 and 23 of the engine block. The ports 26 and 27 may be of any length circumferentially about the sleeve desired, in order to render the intake and exhaust most efficient. These ports, however, are horizontally elongated as illustrated in Figure 4 of the drawings.

Referring to the means H and L for slideable operation of the sleeve valves G, the principle of operation thereof is substantially the same as set forth in my co-pending application, Serial No. 128,651, filed August 11, 1926, and further described in my United States Patent 1,286,275, issued December 3, 1918, and also my co-pending application, Serial No. 61,722, filed October 10, 1925.

As to the cam means H, the same includes a cam shaft 30 longitudinally bearing in the crank case C, operated in any approved manner, as by means 31 from the said crank shaft. For each sleeve valve the cam shaft 30 is provided with main and auxiliary cams 32 and 33, having throw portions as set forth in my co-pending application, Serial No. 128,651, the operation of said cams being exactly as described in said co-pending application.

As to the means L upon which the cams 32 and 33 operate, the same includes structure identically as set forth in my co-pending application Serial No. 128,651, filed August 11, 1926, including a crescent-shaped frame 38 pivoted at 41 upon the casing structure of the engine and including a forwardly extending half circled supporting arm 45 and above the same a quarter circled arm 46 rigid with the arm 45. The free ends of the arms 45 and 46 are spaced. At its free end the longer arm 45 has a slot 49 radially opening outwardly within which is slidably received a pin 50 carried by the lower end in a laterally projecting relation from the sleeve valve G.

The lower or longer arm 45 between its ends, substantially midway is provided with an anti-friction roller 53, and at its free end the shorter arm 46 is provided with a pivoted arm 57, which between its ends supports an anti-friction roller 66, eccentric to the pivot axis of the arm 57. Spring means 63 is provided, normally urging the roller 66 towards the roller 53. In operation the roller 66 operates on the cam 32 and the other roller 53 operates on the cam 33, as is well described in my co-pending application above referred to.

As before mentioned a cylinder head M is provided in connection with each cylinder of the engine A. Each cylinder head comprises

an outer substantially cylindrical shaped shell 80, which is insertable downwardly into the upper end of the cylinder chamber 15, so that the outer circumference thereof is spaced from the inner surface of the walls of the cylinder chamber 15, to provide an annular compartment 81 which extends longitudinally along the upper portion of the cylinder chamber 15, and into which the upper end of the sleeve valve G extends. The upper margins of the other shell 80 are provided with laterally extending attaching flanges 82, secured over the top surface of the cylinder block B and provided with openings 83 therethrough for receiving attaching bolts 84 by means of which to secure the respective cylinder heads in place on the cylinder block B, as is well illustrated in Figure 5 of the drawings. These flanges 82 are provided with transverse apertures 86 therethrough aligning with the openings 19 thru the top wall of the cylinder block B, and thru which water passes into the compartment 90 of the water receiving hood P.

An inner shell 91 is also provided as part of each cylinder head M, which is of tubular formation, and extends centrally upward thru the passageway 92 provided thru the outer shell 80. This inner shell 91 is integral at its lower end with the lower end of the outer shell 80, and from this connection illustrated at 94 in Figure 2 of the drawings, the inner shell 91 extends upwardly in spaced relation with the inner walls of the outer shell to provide an annular space 95 open at the top of the compartment 90 of the water hood P, so that water may enter and circulate about the space 95 to cool the upper portion of the sleeve valve and reciprocating parts of the sleeve valve operating mechanism, as well as to generally cool the entire upper part of the cylinder in a novel relation.

The inner shell 91 is provided with a downwardly facing frusto-conical compartment 98, which is of greatest diameter at its outlet into the chamber within the sleeve valve G and tapers in a converging relation therefrom upwardly to a spark plug supporting wall 99 which is integrally provided in the shell 91 at a location about one-third the distance above the lower edge of said inner shell. This wall 99 is provided with a screw threaded opening 100 therethrough for detachably receiving a spark plug 101, so that the electrodes of the spark plug may depend into the upper reduced end of the tapered compartment 98 of the cylinder head M.

A transverse web portion connects the inner and outer shells 91 and 80 to provide an intake port 105 transversely thru the cylinder head M, which aligns directly with the intake port 22 of the cylinder block B for the respective cylinder in which the cylinder head M is assembled, so that inflowing fuel charge passes thru the ports 22 and 105 into the up-

per or smaller end of the tapered compartment 98. It is to be noted that the intake port 105 is relatively long transversely about the cylinder head M and the intake port 105 tapers in a constricted relation towards the center of the compartment 98, as is illustrated by the tapered sides 110 in Figure 6 of the drawings. Also, the web portion connecting the inner and outer shells is downwardly sloped from the bottom of the intake port 105 to provide a downwardly sloping surface 112 from the outer edge of the intake port 105 to the intersection of the surface 112 with the upwardly tapered surface which defines the tapered compartment 98, as is well illustrated in Figures 1, 2 and 7 of the drawings. It is to be noted that the intake port 105 is flush with the lower surface of the wall 99 so that the inflowing charge will pass directly onto the electrodes of the spark plug 101, and be whirled about in a turbulent flow within the tapered compartment 98, due to the manner in which the same enters the compartment 98 and due to the shape of said compartment 98.

The outer shell 80 at a location above the intake port 105 is provided with an annular groove 114 wherein a preferably expansible packing ring 115 is received, which engages in a sealed connection with inner wall of the sliding sleeve valve G, to seal against leak of compression above the intake port 105. Below the intake port 105 the outer shell 80 is also provided with an annular groove 117, wherein an expansible packing or piston ring 118 is adapted to be received, in a sealed engagement with the inner wall of the sleeve valve G, below the intake port 105. This piston ring 118 is formed as best illustrated in Figure 7, with reduced flanges 119 at the top and bottom margins thereof, which engage the exterior surfaces of the outer shell 80 above and below the groove 117, in order to best anchor the packing ring in position to provide the most efficient seal. It is to be noted that the packing ring 118 is considerably wider than the upper packing ring 115, and this is provided because of the vertically offset relation of the intake and exhaust ports of the sleeve valve G, which the piston ring 118 is adapted to seal at different locations in the sliding movement of the sleeve valve.

The inner tubular shell 91 extends at its upper end above the top surfaces of the top wall of the cylinder block B and above the top surface of the flanges 82 of its cylinder head M. Adjacent to the plane of the top surface of the flanges 82, each cylinder head M on the inner shell 91 thereof is provided with an annular hood supporting flange 120 which provides an upwardly facing shoulder. The upper end of the shell 91 above the flange 120 is externally screw threaded for

detachably receiving a hood clamping nut 122.

The water hood P extends the length of the engine A, and the same is provided with side walls 125, which extend along opposite sides of the engine. It is furthermore provided with a top wall 126, and for each cylinder head M the hood top wall 126 is provided with a depending tubular extension 128 which extends downwardly into the compartment 90 of the hood, for freely receiving the upper end of the inner shell 91 of the respective cylinder heads M; the lower edges of each of the tubular portions 128 resting on the supporting flange 120 of the respective cylinder head with which it cooperates, in order to properly support the hood P in position against eccentric clamping action. In this position the lower flanged ends of the side walls 125 rest on the top surface of the top wall of the cylinder block B, and packing 130 is preferably provided between the abutting edges at the bottoms of the side walls 125 and the top wall of the cylinder block B, to provide a liquid seal. In this position the top screw threaded ends of the inner shells 91 extend above the top surface of the top wall 126, for receiving the nuts 122 which are then clamped against the top wall of the hood, to hold the latter in place. Washer arrangements 135 are provided at the location where the tubular shells 91 leave the hood, which the nuts 122 force into engagement with the top wall of the hood about each inner shell 91 to seal the juncture and prevent leakage. The hood P may be provided with any suitable connection 140, illustrated in elevation in Figure 3, which may be connected with the water cooling radiator (not shown).

In so far as the individual cylinder head construction for each cylinder is concerned, it is apparent that the same not only admits of better access to the working parts of the engine, but due to the novel arrangement thereof, the fuel charges inlet so as to maintain the spark plug electrodes clean at all times. The sleeve valve is maintained in a compression sealed relation in the annular groove provided between the cylinder walls and the cylinder head. The single longitudinally extending hood construction cooperates with all of the individual cylinder heads to provide means for efficiently permitting the proper circulation of water throughout the various cylinder heads and through the water circulating jacket of the engine.

Various changes in the shape, size, and arrangement of parts may be made to the forms of invention herein shown and described, without departing from the spirit of the invention or the scope of the claims.

I claim:

1. As an article of manufacture a detachable cylinder head for internal combustion engines comprising an outer substantially

cylindrical shaped shell having a lateral attaching flange thereabout of polygonal formation, the attaching flange inwardly from the outer edges thereof being recessed to provide water passageways, the attaching flanges at the corners thereof having bolt receiving passageways therethrough, an inner shell connected at its lower end in a sealed relation with the lower end of the outer shell and extending upwardly through the outer shell in spaced relation and at its upper end projecting above the attaching flanges of the outer shell.

2. In an internal combustion engine of the class described the combination of a cylinder block having a cylinder chamber therein, a cylinder head for the top of said chamber having a shell projecting downwardly into the chamber and an inner shell projecting within the first mentioned shell and connected in a sealed relation at its lower end therewith, the inner shell projecting upwardly above the top of the block, the cylinder block being jacketed to provide a water space therein and being provided with top ports as outlets from the water space, the cylinder head including a top flange overlying the upper surface of the cylinder block, said top flange being provided with recesses inwardly from the outer edge thereof to define passageways adapted to align with the ports of the cylinder block to permit the passage of water therethrough, a detachable water hood for the cylinder block to guide the circulation of water between the cylinder block and cylinder head, and means for clamping the hood in a leak-proof connection upon the cylinder block and cylinder head.

40 LUTHER A. GAW.
